UNITED STATES PATENT OFFICE.

LORENZ MUTHER, OF NEWTON, AND FREDERICK S. GLINES, OF LYNN, MASSACHUSETTS; SAID GLINES ASSIGNOR TO SAID MUTHER.

FOLDING-MACHINE.

1,092,123.

Specification of Letters Patent. Patented Mar. 31, 1914.

Application filed August 8, 1913. Serial No. 783,769.

To all whom it may concern:

Be it known that we, LORENZ MUTHER and FREDERICK S. GLINES, citizens of the United States, residing, respectively, at Newton, in the county of Middlesex and State of Massachusetts, and at Lynn, in the county of Essex and said State, have invented certain new and useful Improvements in Folding-Machines, of which the following is a specification, reference being had to the drawings accompanying the same and forming a part thereof.

Our improvements relate to new and novel mechanism for folding the edges of flexible material such as leather cloth and the like, and are improvements upon the invention of William F. Lautenschlager, as disclosed in application Serial No. 763,828, filed April 26, 1913, folding machines.

20 The objects of our invention are to provide a device to coöperate with the feeding foot which will enable the operator to decrease the pressure on the feeding foot to permit a certain amount of slip upon the material being folded, the decrease in pressure to take place when material having a convex edge is being folded, and further to provide a means for crimping or creasing the edge of the material being folded so that the edge 30 may be uniformly puckered when convex edges sharply curving are being folded.

In the drawings forming a part of this specification, Figure 1 is an end elevation of a part of the folding machine with the presser foot and slitting device and other parts removed so as to more clearly show the feed point and fold presser; Fig. 2 is a side elevation of the front portion of a folding machine showing the feed point, feed 40 roll and fold presser; Fig. 3 is a view of the fold presser removed from the machine looking upwardly underneath it; Fig. 4 is a side view of the fold presser foot shown in Fig. 3; and Fig. 5 is a view of a piece of material 45 which has been folded showing convex curvature and showing the creases in the edge portion which was folded over upon the body part.

In the drawings forming a part of this specification, 1 represents the upper portion of the frame of the machine and 2 the lower portion of the frame, which portions contain the fold operating mechanisms for folding the edge of a flexible material. In 55 folding the convex edges of a flexible ma-

terial, especially where the curvature of the edge is of the diameter of a small circle, it is desirable that it be fed forward over short distances much shorter than material having a straight or concave edge. In some instances the movement of the feed point is shortened, but we prefer to have the movement of the feed point the same at all times, but with decreased pressure of the feed point upon the material, so that it will slip on its surface and thus shorten the feeding movement. To accomplish this purpose we provide the following mechanism: The feed point and its operating mechanism in our improved folding machine is exactly the same as that shown in the Lautenschlager application, Serial No. 763,828, but with the following addition. To the feed point 3 and shaft 4 with its clamping collar 5 we insert a pin 6 in the collar 5 against which the cam surface 7 of the cam 8 will bear when the mechanism to move the feed point downwardly is at its lowermost point. The cam 8 is pivoted upon the pivot 9 and has a projecting handle 10 formed so that the fingers of the operator may press upon it and by depressing the handle 10 bring the cam surface 7 upwardly to a point where the pin 6 will bear upon it and prevent the feed point 3 from bearing with its full pressure upon the material being folded. The lever 10 is held upwardly by means of a spring 11 which is mounted back of and secured by block 12 to the frame of the machine by the screw 13. The block 12 has a projecting portion 14 containing an adjusting screw 15 which may be adjusted up or down to permit the lever 10 to be depressed more or less to decrease or increase the pressure of the feed point 3 upon the material.

The decreasing of the pressure of the feed point 3 upon the material to a more or less extent provides for more or less slippage of the feed point on the material to shorten or lengthen the feeding movement of the material according as the curvature of the convex surfaces being folded is more or less. In conjunction with this device for increasing and decreasing the feed of convex edges of material we provide a creaser 16 which is movably mounted in the fold presser 17 at its fold pressing surface 26. This creaser 16 has an angular portion 19 which is shown in Fig. 1, with a hole in it so that it may be mounted upon the screw 20, and held down-

wardly by means of the spiral spring 21 which is mounted around the screw 20, its upper end bearing under the head of the screw 20 and its lower end upon the creaser 16. To turn the screw 20 in or out increases or decreases the tension of the spring 21 upon the creaser 16, thereby increasing or decreasing the depth of the crease in the edge of the material. The creases are shown 10 in the material 22 as 23, 23, etc. The object of providing these creases is so that the edge of the material will pucker regularly or at regular intervals and make a flatter surface at the folded edges than it would otherwise 15 do if the material was not creased, for the reason that several puckers might otherwise come close together with intervals between the groups what were comparatively flat, where the several puckers come together the 20 folded edge would be thick and the intervals without puckers thin, thus producing an uneven appearance.

The creaser 16 might be rigidly attached to the fold presser end 18 and would work 25 very nearly as well, but we prefer to flexibly attach it as shown at Figs. 3 and 4 so as to provide for increasing or decreasing the depth of the creases corresponding to the different thicknesses of material being 30 folded.

In operation the cam 8 and lever 10 forming a part of it is shown in position indicated in Fig. 2, and this provides for the full pressure of the feed point 3 upon the material, but when the convex curved edge is fed to the feed point 3, the finger of the operator may be placed upon the lever 10 and the lever depressed until it comes in contact with the adjusting screw 15. This prevents the 40 spiral spring 24 from pushing the feed point 3 downwardly to its full throw, by reason of the pin 6 contacting with the cam surface 7 before the feed point has completed its full throw, thus relieving the pressure upon the 45 material, and this pressure upon the material may be adjusted by moving the adjusting screw 15 up or down to decrease the

downward movement of the lever 10. The creaser 16 it will be noted projects outwardly beyond the edge 25 and downwardly beyond the surface 26 of the fold presser 17, as shown in Fig. 4, so that creases or crimps are made in the edge of the material before the fold is pressed upon the body of the material by the fold pressing surface 26. 55

The angle and location of the creaser 16 may be varied with reference to the edge 25 of the fold presser without departing from the spirit of our invention; likewise it may be rigidly attached rather than flexibly or 60 removably attached and the shape of the cam surface 7 of the cam 8 as well as the location of the cam may be varied without departing from the spirit of our invention. 65

What we claim is:

1. In a folding machine, a feed point and a movable fold presser combined with means mounted on the movable fold-presser for creasing and crimping the edge of the material being folded in advance of the fold 70 pressing operation.

2. In a folding machine, a feed point and a fold presser combined with yielding means mounted on the fold-presser to crease and crimp the convex curving edges of the material and means for varying the pressure of the feed point on the material being folded. 75

3. In a folding machine, feeding means and a movable fold-presser combined with 80 yielding means mounted on the fold-presser and projecting beyond the fold presser surfaces thereof to crease and crimp the edge of material operated upon in advance of the fold pressing operation. 85

In witness whereof, we have hereunto set our hands, in the presence of two subscribing witnesses, this the fifth day of August, 1913.

LORENZ MUTHER.

FREDERICK S. GLINES.
